BOTTLE

Arnold I. Lorenzen, deceased, late of Toledo, Ohio, by Gertrude M. Lorenzen, executrix, Toledo, Ohio, assignor to Owens-Illinois Glass Company, Toledo, Ohio, a corporation of Ohio

Filed Apr. 15, 1964, Ser. No. 79,520

Term of patent 14 years

(Cl. D58—8)

The back not shown is the same as the front shown. The dominant features of this design reside in the configuration shown in full lines on the drawing.

What is claimed is:

The ornamental design for a bottle, substantially as shown and described.
